UNITED STATES PATENT OFFICE.

ALGERNON DEWHURST, OF SKIPTON, COUNTY OF YORK, ENGLAND.

THREAD-CASE FOR SEWING-MACHINES.

SPECIFICATION forming part of Letters Patent No. 324,240, dated August 11, 1885.

Application filed June 23, 1885. (No model.) Patented in Eng'd and April 29, 1885, No. 5,328.

To all whom it may concern:

Be it known that I, ALGERNON DEWHURST, a subject of the Queen of Great Britain and Ireland, and a member of the firm of John Dewhurst and Sons, residing at Skipton, in the county of York, cotton-spinners and sewing-cotton manufacturers, have invented certain Improvements in Thread-Cases for Sewing-Machines or for other Purposes, (for which I have applied for patents in Great Britain on the 29th April, 1885, No. 5,328; France on the 28th May, 1885, and Belgium on the 29th May, 1885,) of which the following is a specification.

15 My invention has for its principal object to provide cases containing coils of cotton or other thread for use in the shuttles of sewing-machines—such, for example, as that known as the "Singer oscillating-shuttle machine;" 20 but the said cases containing coils may be used for any other purpose for which they may be applicable, and the essential feature of my invention is the provision of a free passage within the case for the thread from 25 the center of the coil to the periphery of the case, from which part it is drawn off in use.

Figures 1 and 2 of the accompanying drawings represent, respectively, an elevation and a transverse section of a paper and card-board 30 case and inclosed coil of thread, the case being provided with a free passage for the thread, as aforesaid.

The coil of thread to be inclosed in the case is shown in Fig. 3. The case by which it is 35 inclosed is made up of two card-board side disks, which are placed one on either side of the coil of thread.

The disk, Fig. 4, is a plain disk, but the other, Fig. 5, has a gap, a , extending from 40 the center and out at the side. Over this latter disk the ticket, Fig. 6, is pasted. Fig. 7 shows a plan and section of this disk and ticket gummed together. The gap a is placed over the end of the thread b , which lies along 45 the side of the coil from the center to the periphery, the gap a giving a free passage for the thread between the side of the thread-coil and the ticket, as shown in Fig. 2, which is enlarged for the purpose of showing this more 50 clearly. The two disks are joined by a strip,

Fig. 8, which is made of a strip of card-board, Fig. 9, gummed to a wider and longer strip of paper, Fig. 10, having a slit in it at c for the passage of the thread. The card-board strip is not long enough for its ends to meet 55 round the periphery of the coil, so that there is a gap, d , left between the ends for the thread, the said gap forming a continuation of the gap a in the side disk.

Fig. 11 shows the combined strip placed 60 ready for the sides of the paper portion to be gummed to the two disks, Fig. 1 showing the coil and case completed by this operation.

Figs. 12 and 13 represent views at right angles to each other of a metal case made up 65 of two disks, one placed as in Fig. 14, and the other (shown in Fig. 15) having a passage, a^2 , for the thread on its inner side. The said disks are placed one on each side of the coil, and are joined by a strip, Fig. 16, with ears, 70 which are bent down over the disks to secure the parts together, in a manner like that by which the parts are secured by the paper strip in the preceding example. The passages inside the case for the free passage of the thread 75 are made by stamping up the groove or depression o o^2 in the one disk in line with a groove or depression, d^2 , in the side strip, which has also a slot, c^2 , for the passage of the thread to outside the case. 80

I claim—

1. A thread-case for sewing-machines, provided on the inside with a free passage or channel for the thread, said channel being formed in one of the sides of said case, and 85 extending from the center to the periphery thereof, substantially as described.

2. A case for containing a coil of thread, the same comprising end disks, one of which has a thread passage or channel extending 90 from its center to its edge, and a strip connecting said disks and forming the periphery of the case, substantially as described.

3. A cylindrical thread-case having in one of its circular ends a channel or passage for 95 the thread running from the center to the edge thereof, the periphery of said case being also provided with a channel or passage forming a continuation of that in the end of the case, substantially as described. 100

4. A thread-case comprising two disks of card-board or similar material, one having a gap extending from its center to its edge, a disk of paper placed over said disk, and a connecting-strip formed of a card-board strip and a paper strip, the former being shorter than the circumference of the case, so as to leave a thread-passage communicating with that in the end of the case, substantially as
5 described.
10

In testimony whereof I have signed my name to this specification in the presence of two subscribing witnesses.

ALGERNON DEWHURST.

Corrections in Letters Patent No. 324,240.

It is hereby certified that in Letters Patent No. 324,240, granted August 11, 1885, upon the application of Algernon Dewhurst, of Skipton, England, for an improvement in "Thread-Cases for Sewing Machines," errors appear in the printed specification requiring correction as follows: In line 66, page 1, the word "placed" should be stricken out and the word *plain* inserted instead, and in line 77, same page, the reference letters "o o²" should be stricken out and the reference letter *a²* inserted instead; and that the said Letters Patent should be read with these corrections therein that the same may conform to the record of the case in the Patent Office.

Signed, countersigned, and sealed this 8th day of December, A. D. 1885.

[SEAL.]

Countersigned:

M. V. MONTGOMERY,
Commissioner of Patents.

H. L. MULDROW,
Acting Secretary of the Interior.
